US0D1015362S

(12) **United States Design Patent** (10) Patent No.: **US D1,015,362 S**
(45) Date of Patent: ** Feb. 20, 2024

(54) **DISPLAY SCREEN WITH GRAPHICAL USER INTERFACE**

(71) Applicant: **MEDICALTEK CO., LTD.**, Taichung (TW)

(72) Inventors: **Yen-Yu Wang**, Taichung (TW); **Chieh-Chu Chen**, Taichung (TW); **Jing-Ying Huang**, Taichung (TW)

(73) Assignee: **MEDICALTEK CO., LTD.**, Taichung (TW)

(**) Term: **15 Years**

(21) Appl. No.: **29/798,519**

(22) Filed: **Jul. 8, 2021**

(51) LOC (14) Cl. **14-04**

(52) U.S. Cl.

USPC **D14/486**

(58) **Field of Classification Search**
